MICROSCOPE

John T. Armbruster, Niagara Falls, N. Y., assignor to
American Optical Company, Southbridge, Mass., a voluntary association of Massachusetts

Application February 26, 1957, Serial No. 44,990

Term of patent 14 years

(Cl. D57—1)

Fig. 1 is a perspective view of a microscope, showing my new design. This view is taken from one side and forwardly of the microscope.

Fig. 2 is a perspective view taken from the other side and rearwardly of the microscope.

Fig. 3 is a top plan view thereof.

The dominant features of my design reside in the portions shown in full lines in the drawing.

I claim:

The ornamental design for a microscope, substantially as shown and described.
